UNITED STATES PATENT OFFICE.

JAMES A. CHRISTY, OF SAN FRANCISCO, CALIFORNIA, ASSIGNOR, BY DIRECT AND MESNE ASSIGNMENTS, TO THOMAS W. COSGROVE, BERNARD SHRAFL, FRONA EUNICE WAIT, AND E. J. BALDWIN, OF SAME PLACE.

TELEPHONE.

SPECIFICATION forming part of Letters Patent No. 480,656, dated August 9, 1892.

Application filed December 1, 1890. Renewed October 5, 1891. Serial No. 407,674. (No model.)

To all whom it may concern:

Be it known that I, JAMES A. CHRISTY, a citizen of the United States, residing at San Francisco, in the county of San Francisco and

5 State of California, have invented certain new and useful Improvements in Telephones; and I do declare the following to be a full, clear, and exact description of the invention, such as will enable others skilled in the art to 10 which it appertains to make and use the same, reference being had to the accompanying drawings, and to the letters of reference marked thereon, which form a part of this specification.

15 My invention relates to improvements in telephones, and has for its object the provision of a simple and effective instrument of this sort having features of novelty in the construction, as will be hereinafter explained, 20 and particularly pointed out in the claim.

The accompanying drawings illustrate what I consider the best means for carrying my invention into practice.

Figure 1 is an elevation of the instrument 25 and so much of the stand as is necessary to understand its application and use. Fig. 2 is a sectional view of the instrument. Fig. 3 is an elevation of the mouth of the instrument with the mouthpiece cut off. Fig. 4 is 30 an elevation of the electrode K' removed.

Similar letters of reference indicate corresponding parts in all the figures where they occur.

A is the mouthpiece of the instrument, 35 which is cast in one with the side and front walls of the chamber E, as shown in sectional view, Fig. 2.

B' is the rear wall or plate of the chamber, which has a rim or lip b, which projects over 40 the edge of the part B. The parts B and B' are united by screws, as shown in dotted lines, Fig. 2, or in any other convenient manner.

The instrument is secured to a swinging 45 arm of the stand, as explained and shown in my former application, filed July 12, 1890, Serial No. 358,592, by means of a stud D, screwed over a stud d, formed on or secured in the back of the transmitter. An opening 50 d' is formed in stud D for the arm of stand

to pass into, and a pinching-screw d² serves to fasten the stud at any point on the arm.

In the chamber between the parts B and B' all the operative parts of the instrument are placed. Over the opening a, leading from the mouthpiece A into the chamber, a wire-gauze screen E' is placed for the purpose of breaking the volume of air passing from the mouth of the person speaking into the air-chamber and distributing the air and sound-waves upon the surface of the diaphragm, causing it to vibrate uniformly and not wholly from the center, as if a volume of air unbroken was passing into the mouth of the receiver-instrument. Said wire-gauze also acts as a shield to protect the diaphragm from injury from any instrument that may be thrust in the mouth of the instrument. Upon this screen lies a rubber washer F, on which is supported the diaphragm G, which may be of any suitable material. A metal washer H rests upon the back of the diaphragm, and a thicker rubber washer I rests upon the washer H, and an insulating-ring J surrounds both washers H and I and completely insulates them from both of the side walls of the sound-chamber.

An electrode K, formed of metal, has a ring k resting upon the ring I and has the rear plate B' of the transmitter resting against the rear face. The electrode K consists of ring or washers k, disposed as above described, the sloping walls or dome K' extend forward from the washer in dish-shape, and the disk k², mounted on the dome and presenting its round face to the diaphragm and in close proximity thereto. The disk projects beyond the sides of the dome, which latter is provided with a series of perforations k* k* around it beneath the edge of the disk.

A metal post L, connected at its forward end to washer H, projects through rubber washer I, through ring or washer k, from which it is insulated, and through the back B' of transmitter, from which it is also insulated, and receives the binding-post M, which carries the battery-wire, whereby connection is made to the washer H and through it to the diaphragm. The line-wire is connected in any

suitable manner to the stand, and circuit is through the swinging arm, stud D, back B', and air-distributer K.

K² is the comminuted material.

5 The transmitter as thus constructed constitutes a very sensitive and efficient instrument, from which sounds coming over the wire are spoken out, so that they can be heard a considerable distance from the instrument 10 with as much distinctness as when held to the ear.

It will be understood that the construction 15 of the instrument herein described can be used as well upon a fixed stationary telephone as upon a movable stand, and I do not confine myself to its application to such a stand.

Having thus described my invention, what I claim, and desire to secure by Letters Patent, is—

In a transmitter, a case having a wire-gauze screen over the mouth, an insulating-washer resting on the screen, a diaphragm resting on the washer, a metal washer set upon the diaphragm having electrical connections to the exterior of the case and insulating-washer set upon the metal washer, an insulating-ring surrounding the metal and insulating-washers, and an electrode having a disk in close proximity to the diaphragm, a perforated dome on which the disk is supported, and a washer in contact with the walls of the case, as set forth.

In testimony whereof I affix my signature in presence of two witnesses.

JAMES A. CHRISTY.
